LOCKING MECHANISM

Morden C. Lighter and Fred Lehmann,
San Francisco, Calif.

Application September 17, 1938, Serial No. 230,447

14 Claims. (Cl. 70—433)

This invention relates generally to locking devices or mechanisms of the type making use of bolts or latches for locking movable structures, such as swinging or sliding doors or like closures.

5 It is an object of the invention to provide a locking device of the above character which will perform the usual locking and unlocking functions, and which in addition will afford assurance against unauthorized unlocking operations. In
10 this connection the present invention is characterized by the fact that a record member such as a strip of lead or like soft metal can be introduced into the device immediately prior to a locking operation. This record member is automatically gripped by a marking die, when the device is locked, and it is not released until an
15 authorized locking operation.

Another object of the invention is to provide an improved form of locking mechanism having
20 features tending to offset the possibility of unauthorized locking or unlocking operations.

Another object of the invention is to provide a locking device particularly adapted for use with freight car doors, in place of conventional locking devices and seals, and which will afford utmost protection against unauthorized opening of the car.

Further objects of the invention will appear from the following description in which the preferred embodiment of the invention has been set forth in detail in conjunction with the accompanying drawings.

Referring to the drawings:

Fig. 1 is a side elevational view, illustrating a locking device constructed in accordance with this invention, and applied to a freight car door or like structure.

Fig. 2 is a plan view of a typical stamping or marking die which can be utilized to apply marking to the record member of Fig. 3.

Fig. 3 is a plan view illustrating a record member such as is utilized in conjunction with our device for forming a permanent record.

Fig. 4 is a side elevational view of the device, with the housing cover removed, and showing the working parts.

Fig. 5 is a top plan view of the device as illustrated in Fig. 4, the cover or housing being in cross-section.

50 Fig. 6 likewise is a side elevational view of the device, with the housing or cover being in cross-section, but looking towards the opposite side from that illustrated in Fig. 4.

Fig. 7 is an enlarged cross-sectional detail taken
55 along the line 7—7 of Fig. 6.

Fig. 8 is a perspective view illustrating a key construction which can be utilized in conjunction with unlocking operations.

Fig. 9 is a side elevational view looking towards the same side of the device as illustrated in Fig. 5
6, but showing certain parts in cross-section, and with the parts in unlocked position.

Fig. 10 is a cross-sectional detail taken along the line 10—10 of Fig. 4.

Fig. 11 is a cross-sectional detail taken along 10
the line 11—11 of Fig. 9.

The device as illustrated in the drawings consists of a body 10, which is shown mounted upon a sliding door 11, and which carries a suitable housing 12 for enclosing the working parts. The 15 mounting is provided with an opening or passage 13, for receiving a bolt 14, and this opening extends through the end wall 10a. The bolt or bolt bar 14 is shown attached to the adjacent stationary structure 16, such as the side of a door 20 frame.

As will be presently explained, the working parts include latching means for releasably engaging the bolt bar 14, together with parts under the control of a key, adapted to be manually actuated for an unlocking operation. Briefly, manual operation is carried out by the turning of knob 17 (Fig. 1) and a key 18 is insertable in conjunction with the knob 17, before the knob can be turned.

30 The latching mechanism for locking engagement with the bolt bar 14, includes a pair of latch levers 21. These latch levers have pivotal connections 22 with the upstanding walls 23 of the mounting 10. Their forward ends 24 are adapted 35 to engage within the opening or recess 26, in the bolt bar 14.

As a means for moving the latch levers 21 to the locking position illustrated in Fig. 10, as the bolt bar 14 is thrust into the passage 13, we provide a plunger 27 which is slidably mounted at the rear end of the passage 13. The rear end of plunger 27 is shaped to afford a cam surface 28, and this cam surface is adapted to engage the rear inturned end portions 29 of the latch levers 40 21. Thus when plunger 27 is forced to its rear-most position by insertion of the bolt 14, cam surface 28 by engagement with the latch lever portions 29, causes the latch levers to move to the locking position illustrated in Fig. 10. 50

For the purpose of performing an unlocking operation, we provide additional cam means for engagement with the latching levers 21, and this cam means is under the control of a secondary latch. Thus plunger 27 is attached to the for- 55

ward end of a stem or rod 31, and this rod is slidably carried by the stationary guide sleeve 32. Slidably disposed upon the sleeve 32, there is a cam member 33, which is attached to stem 31 as by means of a pin 34. Cam member 33 is formed to afford a beveled cam surface 36, which is adapted to engage the rear end portions of the latch levers 21 (see Fig. 10). It will be evident that when cam member 33 is forced to the right 10 as viewed in Fig. 10, cam surface 36 engages the rear ends of latch levers 21, thus forcing these levers to dis-engaged position.

The upper part of cam member 33 is cut away to form a shoulder 38 (Figs. 7 and 9) and this 15 shoulder is adapted to engage the secondary latch lever 39. This lever has a pivotal connection 41 with the bracket 42, which in turn is secured to the main mounting 10. Fig. 4 illustrates the secondary latch 39 engaged with shoulder 38. When 20 this latch is moved upwardly it permits cam member 33 to move forwardly to the position illustrated in Fig. 9, which also corresponds to dis-engaged position of the latch levers 21.

In order to transmit motion from the knob 17 25 to the secondary latch lever 39, we provide a motion transmitting lever 43, one end portion 44 of which is adapted to engage a pad 46, secured to the secondary latch 39. Knob 17 is mounted upon one end of a shaft 47 (Fig. 7) and this shaft 30 is journaled to the mounting 10, and carries the cam members 48. These cam members are adapted to engage the fingers 49 on lever 43, whereby when the shaft 47 is turned to rotate cam members 48 one revolution, lever 43 is rocked 35 to lift secondary latch 39 and thus dis-engage this latch with respect to the shoulder 38.

In order that the rotation of shaft 47 shall be properly under the control of a suitable key, that part of the mounting adjacent the knob 40 17 is provided with a passage 51 for the retention of key 18. As an example of the type of key which can be employed, we have shown one 45 formed of a flat strip of metal, having its outer end portion 52 bent laterally to facilitate its introduction and removal. The knob 17 is shown 50 provided with a radial slot 53, whereby it is necessary for the knob to be in one position to enable the key to be introduced or removed. Various types of notching or grooving can be 55 used in order to avoid unauthorized operation. For example the upper surface of the key is shown provided with characteristically formed grooves 54 and 55, and the upper side of the key passage 51 can be contoured in a complementary manner, as illustrated in Fig. 9. Also the key 60 is shown provided with lateral grooving 56, made to match the complementary grooving provided on a member 57 (see Fig. 9) which is mounted upon shaft 47 and which may be integral with the 65 cam members 48. Also the key is shown provided with a rib 58, near its end, which is adapted to be accommodated by the annular groove 59, formed on the annular collar 61. This collar is also mounted upon shaft 47, so that it rotates 70 with rotation of the knob 17. Such engagement with collar 61 serves the purpose of releasably retaining the key in a proper predetermined position in the lock.

In place of forming the key passage 51 in a 75 rigid part of the mounting, it can be formed in a block 62, which is yieldably retained within slots 63 as by means of studs 64 and compression springs 65. Thus block 62 may move downwardly a limited amount against the urge of compression springs 65, in order to facilitate engagement

of the key and particularly to enable the rib 58 to snap into the unbroken annular groove 59.

In order to positively lock knob 17 and shaft 47 against rotation when the key 18 is removed, we provide a lever 66, having a pivotal connection 67 with the mounting 10. This lever swings on an axis at right angles to the axis of shaft 47. It is provided with a pair of lugs 68 and 69 adapted to be accommodated in the slots 71 and 72, formed in the collar 61. A tension spring 73 is attached 10 to lever 66, to urge the same towards the collar 61. Lever 66 is also provided with a finger 74, which extends to a position slightly below the collar 61, to be engaged by the end portion 75 of the key 18 (see Fig. 7). Thus when the key 15 18 is thrust to its operating position, lever 66 is swung to a dis-engaged position with the lugs 68 and 69 dis-engaged with respect to the collar 61.

It is desirable to provide detent means in conjunction with knob 17 and shaft 47, to facilitate manual stopping of rotation of the knob 17 when the slot 53 is in alignment with key passage 51. For this purpose we have shown a leaf spring 76, the free end of which carries a stud 77, engageable with the periphery of the collar 61. At a proper point, the collar 61 is provided with a groove 78, within which stud 77 engages when the knob 17 is in the position illustrated in Fig. 1.

In addition to the foregoing mechanism, we 30 make use of a record member of deformable material, such as lead or lead alloy, which is retained within the device as long as the device is in locked condition, but which is released at the time of unlocking the device. The locking 35 operation not only grips the record member, but in addition applies a permanently indented or embossed marking upon the same as by means of a marking die. A record strip such as can be employed for this purpose is illustrated in Fig. 3. 40 It consists of a simple strip 81 formed of lead or other suitable deformable metal, the outer end portion 82 of which may be enlarged. Some suitable permanent marking is shown applied to portion 82, and this marking may include a serial 45 number 83 and like characters. The mounting is provided with a passage 84 for accommodating the strip 81, and this passage can be arranged in relatively close relationship with respect to the knob 17, as illustrated in Fig. 1. As illustrated in Fig. 9, overlying the strip 81, when inserted within passage 84, there is a plunger 86, the lower end of which carries a marking die 87. The characters or indicia of this die may of course vary in practice, but to illustrate the 50 utility of the present invention, a typical type of marking is illustrated in Fig. 2. In this instance the marking consists of various letters to indicate the transportation company or railroad responsible for the shipment of the goods, plus a number which may indicate the particular freight car or the shipping container being locked. A sleeve 88 is shown forming a guide for plunger 86, and this sleeve may be formed as a part of the 55 mounting 10. The upper end 89 of the plunger 86 engages a lever 91, which has a pivotal connection 92 with the mounting 10. A compression spring 93 serves to normally urge the plunger 60 65 66 towards retracted position.

Cooperating with the lever 91, there is a rock 70 lever 94, having a pivotal connection 95 with the bracket 96. Lever 94 carries a yoke or fork 97, the ends of which are provided with slots 98 to accommodate pins 99. These pins are secured to 75

and extend laterally from the cam member 33 (Fig. 10).

To form a motion transmitting connection between arm 91 and rock lever 94, a roller 101 is journalled to the rear end of rock lever, and is adapted to engage the upper surface of arm 91. Also the arm 91 is shown connected to the rear end of rock lever 93 by means of links 102. To insure proper coordinated movements of rock lever 94 and lever 43, the latter lever is shown provided with a finger 103 which is adapted to engage the rear end of rock lever 94, during an unlocking operation. To return plunger 86 to the position shown in Fig. 9, spring 93 is provided between the upper collar of sleeve 88 and portion 89 of plunger 86.

As a further precaution against unauthorized locking operations, we provide elements making necessary the use of a particular type of bolt bar. Thus the particular type of bolt bar 14 as illustrated is provided with an opening 106 extending laterally through the same. Above the bolt passage 13 there are two members 107 and 108, which have pivotal connections 109 and 111 to the mounting 10. Member 107 is in the form of a curved arm as illustrated, with an enlarged end portion 112. Member 108 is formed to provide two fingers 113 and 114, the latter of which is adapted to engage the inner curved surface 116 of the member 107. Member 107 is also provided with a cam finger 118, adapted to engage the curved surface 119 on the member 108. When member 107 is swung in a counter-clockwise direction from the position illustrated in Fig. 9, finger 118 engages cam surface 119, thus causing counter-clockwise rotation of member 108. This is what occurs upon insertion of the bolt bar 14. Counter-clockwise rotation of member 108 is accommodated by the slot or openings 106 in the bolt bar. Thus when the bolt bar is in locked position, finger 113 extends entirely through the slot 106, as illustrated in Fig. 6. Conversely, when the bolt bar is retracted after an unlocking operation, the movement which it imparts to the member 108 is accommodated by clockwise swinging of member 107, to position illustrated in Fig. 9. It will be evident that this arrangement makes it impossible to introduce a bolt bar into the passage 13, which is not provided with the lateral slot 106, to accommodate finger 113. Should one attempt to introduce a solid bolt bar into passage 13, portion 112 would in effect form a solid obstruction.

Operation of the complete device can now be outlined as follows:—Before a locking operation the parts are as illustrated in Fig. 9, with secondary latch 39 dis-engaged with respect to the shoulder 38, with the knob 17 in the position illustrated in Fig. 1, and the members 107 and 108 occupying the positions illustrated in Fig. 9. When the bolt bar 14 is thrust into the passage 13, either by movement of the bolt bar with respect to the main part of the device, or by movement of the device toward the bolt bar, the end of the bolt bar engages plunger 27, and movement of this plunger is imparted to cam member 33, to cause release of latch levers 21, whereby these levers lock with the bar 14 as illustrated in Fig. 10. At the same time the secondary latch 39 is locked upon shoulder 38, and rocking movement of lever 94 is transmitted through arm 91, to cause plunger 86 to be forced downwardly, thus striking the stamping die 87 upon the record member 81. The record member 81 is now firmly locked in place, and it can not

be removed without a complete unlocking operation. Assuming now that one desires to carry out an unlocking operation, the key 18 is inserted substantially as illustrated in dotted lines (Fig. 7) to cause lever 66 to be moved to disengaged position, thus permitting rotation of knob 17 and shaft 47. The operator now turns knob 17 one revolution and during this turning movement lever 43 is rocked to lift the secondary latch 39, thus dis-engaging the cam member 33, and at the same time rock lever 94 is moved in a counter-clockwise direction as viewed in Fig. 9, to cause elevation of the plunger 86, with release of the record member 81. As previously pointed out, such movement of the cam member 33 causes the latch levers 21 to be moved to dis-engaged position, thus releasing the lock bolt 14 for removal. Likewise upward movement of the plunger 86 releases the record member 81, so that this member can be removed to form a permanent record.

A further protective feature of our locking mechanism is provided as shown in Fig. 9. We have provided an insert passage 115 through the outer portion of the housing 12 for accommodating the strip 81. When strip 81 is inserted in this passage it underlies key 18 and when fully inserted also underlies the stamping die 87. The key 18 which is used in conjunction with a lock embodying this arrangement bears on the lower side thereof some suitable permanent marking which indicates the identity of the unlocking station.

Operation of this feature of the device is identical with the previous explanation except that the strip 81 is inserted in passage 115. It has been previously explained that rotation of knob 17 causes rotation of cam members 48, which are adapted to engage the upper surface of key 18. It will be recalled that key 18 is positioned in block 62 which is yieldably retained in slots 63. Thus rotation of knob 17 causes cams 48 to engage the key member 18 and urge it downwardly forcing key 18 into contact with strip 81 and causing the permanent marking on the lower side thereof to be impressed upon strip 81. This arrangement thus makes possible the recording of both locking and unlocking stations on a single strip 81.

It will be evident that the device as described above can be used to advantage in many instances, as for example on freight car doors or the doors of motor trucks. When so used it will afford insurance against unauthorized tampering, and at the same time it will afford a permanent record which is available only after an authorized unlocking of the device.

We claim:

1. In combination with a locking device having mechanism capable of locking and unlocking operations, a member of deformable material adapted to be inserted into the device prior to a locking operation, and means for automatically making an impression upon said member by deformation of the same, said means serving to grip said member while the mechanism remains locked, and means automatically releasing said member and making another impression thereupon carrying out an unlocking operation.

2. In combination with a locking device having bolt-engaging mechanism, a member movable for carrying out unlocking operations, a record member of deformable material adapted to be inserted into the device prior to a locking operation, means for automatically making an impres-

- 5 sion upon said member by deformation of the same and for gripping said member while the device remains locked, and means for automatically releasing said record member and making another impression thereupon upon carrying out an unlocking operation by movement of said member.
- 10 3. In combination with a locking device including mechanism serving to perform an automatic locking operation and a member movable for carrying out unlocking operations, a member of deformable material adapted to be inserted into the device prior to a locking operation, means for automatically making an impression upon said member by deformation of the same, said means
- 15 15 serving to retain and grip said member while the lock remains in locked condition, means for automatically releasing said last-named member upon carrying out an unlocking operation, and means for momentarily gripping said member of deformable material during said unlocking operation.
- 20 4. In a device of the character described, latching mechanism adapted to releasably engage a cooperating bolt, mechanism made operative by insertion of a key in said device for effecting release of said latching mechanism, said last named means including a manual operating member rendered effective only upon insertion of said key, means forming a passage in said device for the
- 25 30 reception of a member formed of deformable material, and means for automatically making an impression upon said last named member upon establishing locking relationship with a bolt, said last named means serving to grip said member
- 35 35 while the latching mechanism remains locked with respect to the bolt, and means for effecting release of said last-named means upon turning said manual operating member to effect release of said latching mechanism.
- 40 5. In locking means of the character described, a body formed to afford a passage for reception of a bolt, a pair of oppositely disposed latches adapted simultaneously to establish locking engagement with the bolt to prevent its withdrawal, and a secondary latching means adapted to be released to effect simultaneous release of said first-named latching means.
- 45 55 6. In a device of the character described, a body formed to afford a passage for reception of a bolt, a latch adapted to have locking engagement with said bolt, a member adapted to retain said latch released with respect to said bolt, said member being movable to disengaged position with respect to said latch by thrusting said bolt into said passage.
- 60 65 7. In a device of the character described, a body formed to afford a passage for receiving a bolt or bar, a pivoted latch adapted to have locking engagement with the inner end of said bolt, a member movably carried by said body and movable from one position in which it retains said latch in disengaged position with respect to the bar to another position in which said latch is released to have locking engagement with said bar, and means engaged by said bar when said bar is thrust into said passage for effecting movement of said member from said first to said second position.
- 70 75 8. In a device of the character described, a body formed to afford a passage for slidably receiving a bolt or bar, a latch pivotally carried by the body, and capable of moving from a released position to an engaged position to lock with the bar, a member movably carried by the body, and movable from a position in which it

10 retains the latch in disengaged position, to a second position in which the latch is released to engage with the bar, a secondary latch adaptable to releasably engage said member, to retain said member in disengaged position with respect to said latch, means engaged by the bar when the bar is thrust into said passage for moving said member to said last named position, and engagement with said secondary latch, and manually operated means for effecting release of said secondary latch.

15 15 9. In a device of the character described, a body formed to afford a passage for receiving a lock bar, a latch pivotally carried by the body, and movable between disengaged and engaged position, the latch when in engaged position serving to lock the bar within said passage, a latch retaining member slidably carried by the body, said member in one position of the same retaining said latch disengaged and when moved to a second position serving to release said latch to lock said bar, means actuated by thrusting the locked bar into said passage for moving said latch retaining member from engaged to released position, a secondary latch automatically engaged by said latch retainer and serving to retain said latch retaining member in its second position, controlled means for effecting release of said secondary latch, and for forcing said latch retaining member from its second to its first position to effect retraction of said first-named latch, means forming a strip-receiving passage in said body adapted to receive a strip of deformable material, and means actuated by movements of said latch retaining member from its first to its second position, for forcing an impression die against said strip with an interlocking engagement, whereby a distinctive impression is made upon said strip and said strip is locked by said die within said strip receiving passage until released by a manual unlocking operation.

20 25 10. In a device of the character described, a body formed to afford a passage to receive a lock bar, a lock bar adapted to slidably fit within said passage and formed to afford a slot extending laterally through the same, and a pair of members pivotally carried by said mounting adjacent said passage, the first of said members having one portion thereof extending into said passage whereby insertion of said bar in said 30 passage moves the same to an out-of-the-way position, the first member having portions cooperatively engaging the second member, whereby when the first member is moved between said two positions said second member is likewise 35 moved between two operating positions, said second member having a portion extending into the slot of said bar for that position of the same corresponding to an out-of-the-way position of the first member.

40 45 11. In a lock of the character described, a body provided with a passage-way for introduction of a lock bar, said lock bar being provided with a slot extending laterally through the same, latching means carried by the body for releasably locking with respect to said bar, and means including a member normally extending into said slot when said bar is in its locked position, and serving to prevent introduction of a lock bar into said passage which is not provided with 50 a lateral slot through the same.

55 60 12. In a device of the character described, latching mechanism adapted to releasably engage a cooperating bolt, mechanism made operative by insertion of a key in said device for 65

effecting release of said latching mechanism, said last named means including a manual operating member, means forming a passage in said device for the reception of a member formed of deformable material, and means for automatically making an impression upon said last named member upon establishing locking relationship with a bolt, said last named means serving to grip said member while the latching mechanism remains locked with respect to the bolt, means for effecting release of said last named means upon turning said manual operating member to effect release of said latching mechanism and means for automatically making an impression upon said member formed of deformable material upon establishing release of the locking relationship with respect to the bolt.

13. A locking device comprising a housing having a passage therein, a latch member mounted on said housing to swing into and out of said

passage, an operating member mounted in said housing to swing into and out of said passage and to hold said latch member out of said passage when said operating member is in said passage, and a bar adapted to enter said passage and having a slot therein spaced from the end thereof in a position to receive said latch member in said passage when the end of said bar has swung said operating member out of said passage.

14. A locking device comprising a housing adapted to receive a locking bar, means in said housing to hold a record, means for marking said record upon the entry of said locking bar into said housing, and key controlled means for marking said record upon withdrawal of said locking bar from said housing.

MORDEN C. LIGHTER.
FRED LEHMANN.
